UNITED STATES PATENT OFFICE.

DAVID C. WILLIAMS, OF BENTON, ILLINOIS.

SPOOL HOLDER.

Application filed March 3, 1923. Serial No. 622,600.

To all whom it may concern:

Be it known that I, DAVID C. WILLIAMS, a citizen of the United States, residing at Benton, in the county of Franklin and State 5 of Illinois, have invented new and useful Improvements in Spool Holders, of which the following is a specification.

This invention relates to a device for holding articles used in sewing, and contains 10 new and useful improvements over similar devices disclosed in my Patents 1,049,021, granted December 31, 1912, and 1,182,827, granted May 9, 1916, the invention residing in the construction, combination 15 and arrangement of parts as claimed.

In the drawing forming part of this application, like numerals of reference indicate similar parts in the several views, wherein:

Figure 1 is a side elevation of the device. 20 Figure 2 is a vertical longitudinal sectional view therethrough.

Figure 3 is a front elevation.

Figure 4 is a detail view partly in section of one of the spool holders. 25

Figure 5 is a similar view of the pivoted member adapted for use in conjunction with the spool holder to retard the rotation of the spool.

The spool holder forming the subject 30 matter of the present invention includes a back plate 10 which has an opening 11 adjacent the upper end thereof, so that the device in its entirety may be suspended from any suitable support. Projecting from the

35 opposed longitudinal edges of the back plate, are parallel flanges 12, and between which flanges I arrange a plurality of spool holders of the construction illustrated in Figure 4 and to be hereinafter fully de-

40 scribed. Supported by the back plate 10 above the uppermost holder is a pin cushion or the like 13 which is provided with a plurality of bendable ears 14 adapted to be received by openings 15 provided in the back

45 plate, after which the ears 14 are bent in a manner to hold the pin cushion immovably associated with said plate. Arranged adjacent the pin cushion is a slotted member 17 which is also provided with bendable

50 lugs 18 adapted to be passed through openings in the back plate 10 and subsequently bent in position to hold the plate and slotted member fixed relatively. The slotted mem-

55 ber supports an angularly disposed tongue 19 for holding a thimble in the manner illustrated in the drawing. The side flanges

12 have their lower edges connected by a transverse bottom piece 20, and this terminates to provide a depending extension 21 which supports a thread cutter, including 60 a blade 22 and a holder therefor indicated at 23. Depending from the bottom 20 and immediately at the rear of the extension 21 is a hook like element 23' from which a pair of scissors may be suspended as will be readily understood.

The device may vary in size to accommodate any number of spool holders, and the latter are arranged between the side flanges 12 as shown. Each holder includes an intermediate body portion 24, and oppositely curved upper and lower portions 25, which are formed with longitudinal grooves or depressions 26. The intermediate body portion 24 is provided with bendable ears 27 70

adapted to be passed through openings in the back plate and bent parallel therewith for holding the spool holders associated with the back plate. The lower curved portion 26 of each holder is formed with a thread 80 receiving slot 28 constituting a guide for the thread. The holders are of a size to accommodate spools of any dimensions, although, the holders may vary in size for this purpose. Associated with each holder 85

is an arcuate shaped plate 29 formed with cylindrical beads 32 one of which is received by one of the grooves or depressions 26, whereby the arcuate shaped plate 29 is permitted free pivotal movement, and 90 always assumes a position to bear against the spool arranged in the holder. This plate being weighted reposes upon the spool to prevent the latter from rotating too freely as the thread is unwound from the 95

spool and each of said plates is provided with a slot 32 through which the thread passes. The weighted plate is so arranged that it is susceptible for use with spools of different dimensions. Arranged between the 100 side flanges 12 and supported thereby is a tubular member 33 which constitutes a pencil support, the member having associated therewith yieldable elements 34 which hold the pencil positioned transversely of 105 the device.

While it is believed that from the foregoing description, the nature and advantages of the invention will be readily apparent, I desire to have it understood that 110 I do not limit myself to what is herein shown and described and that such changes

may be resorted to when desired as fall within the scope of what is claimed.

Having thus described the invention, I claim:

- 5 A device of the character described comprising a rear wall and vertical side walls extending therefrom, a split cylindrical member supported between the side walls and adapted to receive a revoluble object
- 10 therebetween, the split cylindrical member being provided with a longitudinal de-

pression at one side thereof, and a transversely bowed plate arranged within the split cylindrical member, beads formed on one end thereof and loosely received in the depression for pivotal movement, said plate normally resting upon the revoluble object arranged within the cylindrical casing to prevent the same from rotating too freely. ¹⁵

In testimony whereof I affix my signature.

DAVID C. WILLIAMS.
